TARGET STRUCTURE FOR COLOR TELEVISION DISPLAY TUBES

Edwin M. McMillan, Berkeley, Calif., assignor to Chromatic Television Laboratories, Inc., New York, N. Y., a corporation of California

Application October 18, 1954, Serial No. 462,698

10 Claims. (Cl. 313—78)

This invention relates to target structures for use in cathode-ray tubes for the display of television images in color, which utilize post-deflection focusing to concentrate an electron beam on a phosphor which is emissive of a single color. Particularly it relates to structures wherein the electron lenses utilized to focus the beam are the analogs of cylindrical optical lenses, and comprise a single grid of closely spaced, parallel, linear conductors, tightly stretched and mounted adjacent to the display screen, in combination with a conducting coating on the surface of the screen. In tubes of this character a plurality of different phosphors are employed, respectively emissive of different colored light, on impact by the electron stream, the colors being components which additively produce white. The phosphors are disposed in strips extending across the surface of the display screen, generally parallel to the direction of the electrodes of the lens-grid. In a tricolor system, which is the most generally useful, the component colors emitted by the phosphors will ordinarily be red, green, and blue, and a group of strips, including at least one of each of the three phosphors used, is electro-optically centered behind the interspace between each pair of conductors of the grid, the other two phosphors being similarly centered behind the grid conductors.

Because of the fact that, in order to accomplish the focusing, the electrons constituting the beam are accelerated during their passage between grid and screen, their paths in this region are curved toward the axis of the tube and the phosphor groups are therefore not geometrically aligned with the center of deflection of the beam as it scans the screen surface. The amount of deviation of the beam from its rectilinear course increases with its scanning deflection, and this deviation does not increase linearly with either the angle of scanning deflection or its tangent, the latter being proportional to the distance from the center of the grid to the point of penetration thereof by the electron beam.

The factors entering into the problem of electro-optical alignment of the phosphor areas on the screen is discussed fully in the prior art. It is there shown that there are three related quantities which affect the operation of a color television tube of this type. First and most important is the refraction of the beam in its passage between grid and screen. If this is not correctly compensated for in the layout of the screen, the beam may impact not only the wrong phosphor but actually the wrong group of phosphors, rendering the tube inoperative for its intended purpose as color fidelity thus becomes impossible of achievement. The second factor which varies with angle of deflection is the degree through which the beam is concentrated or focused by the electron lens system. The third factor, which is important only in tubes wherein the color displayed is controlled by micro-deflection of the beam at the grid itself, is the sensitivity to such deflection.

In tubes wherein micro-deflection is used the linear

2

conductors of the lens-grid are divided into two interleaved groups, electrically insulated, so that when electrical potentials are applied between the conductors of the two groups the beam is deflected toward the more positive electrode and directed to a phosphor which is electro-optically aligned with the more positive of the two electrodes. The present invention attains its greatest value in tubes of the micro-deflection type, although it is not necessarily limited thereto.

5 It has also previously been shown that by using a more complicated electron lens structure, employing a second grid, and specially shaped screens, all three of the quantities of refraction, focus, and deflection sensitivity may be compensated or made uniform over the entire surface of the screen. It is desirable, however, from the point of view of economy of construction and general utility, to utilize tubes wherein the envelope and screen conformation are more nearly like those employed in the tubes used for the display of monochrome images.

10 Theoretically it is impossible to provide complete compensation of all three of these quantities in a tube employing two-element electron lenses at the lens-grid. The broad purpose of the present invention, however, is to provide a target structure utilizing two-element electron lenses, in which the variations in the electro-optical parameters which affect the performance of a tube of this character are minimized, so that the tube may be operated throughout substantially its full theoretical duty cycle, giving full brilliancy and high operative effectiveness,

15 without employing additional and expensive compensating means to overcome the aberrations of the system. Other objects of the invention are to provide a structure wherein the highly efficient type of color-control grid utilizing tautly stretched wires can be used; to provide a type of target structure wherein the display screen may be deposited directly upon the tube face or window; to provide a device whose construction requires no complex mechanical features and wherein the grid structure can be constructed and positioned in the same general fashion

20 as in the case of planar grids and screens, utilizing only relatively slight modifications; and to provide a type of display tube which has advantages both in lightness, economy of manufacture, and ease of construction over tubes heretofore used.

25 Broadly considered the target structure of the present invention comprises the combination, in a cathode-ray tube which is otherwise of substantially conventional construction, of a lens grid of substantially circular, cylindrical contour, concave as viewed from the electron gun, with a display screen deposited on a surface which is preferably also concave. The lens-grid is composed of tautly stretched, linear conductors, preferably fine wire. The wires are parallel, substantially uniformly spaced, and form elements of the cylindrical surface defined by the grid, their spacing being of the order of magnitude of one elemental area of the television image to be reproduced by the tube. The display screen comprises strips of a plurality of different phosphors, preferably three, which are emissive, upon electron impact, of

30 light of three component colors which additively produce white. The phosphor strips are disposed in groups or color cells, each of which comprises all of the phosphors, one such cell being electro-optically aligned with each interspace between an adjacent pair of wires. As will be shown hereinafter, by proper choice of the radii of curvature of the grid and the screen, it is possible to reduce the variations in sharpness of focus and deflection sensitivity to the same general order of magnitude as the manufacturing tolerances which it is feasible to maintain, and the refraction can be computed and screens constructed to within like tolerances.

In the drawings, illustrative of the detailed descriptions of certain embodiments of the invention which follow:

Fig. 1 is a semi-schematic, axial sectional view in plan of a television display tube embodying the invention, the plane of section being normal to the axis of the cylindrical grid structure;

Fig. 2 is a sectional view through the front end of the tube of Fig. 1, the plane of section being parallel to the axis of the grid;

Fig. 3 is an isometric diagram of one form of frame for supporting a cylindrical grid structure;

Fig. 4 is a fragmentary elevational view of the grid structure, the direction of view being parallel to the cylinder axis.

Fig. 5 is a fragmentary cross-section of the grid structure, taken on the plane 5-5 of Fig. 4, illustrating the means of supporting and connecting to the grid conductors.

Fig. 6 is a fragmentary elevation of the target structure, showing the relationship between the grid conductors and the phosphor pattern at the center of the screen; and

Fig. 7 is a fragmentary cross-sectional view through the target, further showing the relationship between the grid conductors and the phosphor pattern.

Fig. 1 illustrates, diagrammatically, and in exaggerated form, a cathode-ray display tube embodying the present invention. Generally speaking, the tube is conventional in construction with the exception of the grid and screen structure, and it comprises evacuated envelope 1, having a generally funnel-shaped body, and an electron gun 3 mounted in the neck of the funnel. The electron gun may be of any conventional type, embodying a cathode, a control grid, and one or more anodes, adapted to direct a concentrated beam of electrons axially toward the larger end of the envelope. As the gun is conventional it is believed unnecessary to describe it in detail, since any of the many forms which have been devised for the purpose may be used. A base 5 includes plug connections for the various electrodes within the electron gun. In operation the beam is deflected from its axial path about a center of deflection or virtual source 7, to scan the target which forms the novel feature of the present invention. The deflection of the beam may be accomplished by a deflecting yoke mounted to encircle the neck of the tube or it may be accomplished by pairs of deflecting plates within the tube; these equivalents being well understood and the means for accomplishing the deflection not being a part of the present invention are not here shown.

A face plate or window 9 forms the larger end of the envelope. The body of the envelope 1 may be either of metal or of glass. In either case, in tubes of the character here described, the face plate or window 9 is made separately and is connected to the body of the tube at a seal 11 which encircles the envelope. Included in the seal or supported thereby is a ring 12 to which the grid structure next to be described is secured.

In the particular tube illustrated the grid comprises a rigid frame across which are strung two interleaved sets of tightly stretched linear conductors, in practice, most conveniently fine wires. The frame in this case comprises a pair of angles, 13, of structurally strong material. One web 13' at each end of each angle is bent at right angles, to form an abutment against which an insulating end-beam 15 rests, supported by the unbent web, as illustrated in Figs. 3 and 4. The end-beam 15 may be formed of glass or ceramic. It is rectangular in cross-section, one face, that which rests against the webs of the angles 13, is preferably straight, while the other edge, to the right as illustrated in Fig. 4, is a substantially circular arc. This surface is provided with notches 14 at substantially uniform intervals, these notches serving to position the grid wires. The end beams 15 are secured to the angle members 13 by bolts 16, which may also be used to attach the grid to the support ring 12. In the draw-

ing the notches and wires are indicated symbolically, only a few being shown; in an actual tube the grid will comprise 500 or more conductors.

The linear conductors which form the grid are positioned by hooks in a manner best illustrated in Figs. 4 and 5. Two sets of these hooks are used on each of the beams 15. The hooks depend at right angles from continuous strips. One of these strips 17, from which the hooks 17' depend, is clamped between the web 13' and the beam 15, with the hooks extending under the left-hand surface of the beam as illustrated in Fig. 5. The continuous strip 19 of the other set lies at the left of the beam, with the hooks extending above it, as shown in this same figure.

15 The strips 17 and 19 are preferably secured to the beam with insulating cement which reinforces the clamping of the beam to the metal angles 13 insofar as the strip 17 is concerned, and holds the strip 19 in place for winding. A strip of insulation 21 overlies the continuous portion of the strip 19, and may also be temporarily cemented in place. The continuous conductor, in this case a fine wire 23, is then laced around the structure, engaging the hook 17'. The wires are tautly stretched and serve as an additional anchor for the strips 21 and hook strips 19, and the wires being positioned by alternate notches 14. The wires forming a conductor of the second set of grid wires are then laced in place, engaging the hooks 19', these wires passing over the wires of the first set without contact. It may be desirable to interpose additional insulation at the cross-over, or the insulation between the two sets may be accomplished merely by their spacing.

20 This particular structure is shown merely for completeness. Other arrangements can be used which give to the grid as a whole a cylindrical contour. The general arrangement is illustrated in Fig. 4.

25 The relationship of this grid to the bi-directionally curved window 9 of the tube, which is spherical in the case shown, is best illustrated in Figs. 1 and 2. It will be evident upon inspection the grid, in the plane of Fig. 1, is nearly uniformly spaced from the window upon which the fluorescent screen is deposited. In other planes this condition does not hold; it will be seen in Fig. 2 the screen approaches much more closely to the grid at the portions adjacent to the ends of the grid conductors. As 30 will be shown hereinafter this precise arrangement is not a necessary condition for the invention, and the effects of various degrees of curvature of both grids and screen will be discussed in detail.

35 The screen used with this particular arrangement is of a type which is now well known. It comprises narrow strips of different phosphors which are emissive, upon electron impact, of light of three component colors which additively produce white. The phosphors are laid down in a repeating pattern, with the phosphor emissive of one color, preferably green, electro-optically centered between each pair of grid wires, as viewed from the center of deflection 7. A strip of phosphor emissive of one of the other colors, say red, is electro-optically centered behind each of the wires 23, with a strip emissive of the third color, say blue, centered electro-optically behind each of the wires 25. Each pair of wires constitutes an aperture of a cylindrical electron lens. The width of the strips is such that the spacing on centers of the green strips (if the order of the strips is that here described) is equal to or less than the width of one elementary area which is to be resolved in the television image to be displayed upon the tube.

40 The phosphor pattern, as laid out in the manner thus described and illustrated fragmentarily in Figs. 6 and 7, is deposited upon the inner surface of the window 9 as indicated by the reference character 27. Overlying the phosphor coating is a film of conducting material, preferably aluminum, permeable to the cathode-ray beam which traces the television images presented. The dimensions 45 of the phosphor layer and the conducting film which

covers it are too small to be shown in the sectional views of Figs. 1 and 2; the fragmentary views of Figs. 6 and 7, Fig. 6 illustrating the relationship of the phosphor strips to the grid electrode at the center of the screen where the electro-optical alinement and the geometrical alinement coincide, and the cross-sectional view of Fig. 7, are greatly exaggerated for illustrative purposes. As will be seen in these figures there are two green strips 29 for each red strip 31 and blue strip 33.

In Fig. 7 there is shown the conducting film 35, overlying the phosphor coating.

As has been stated, the fragmentary view of Fig. 7 illustrates the position, relatively, of the grid electrodes and the phosphor strips at the screen center, where geometrical, optical, electron-optical positions coincide. In operation the grid wires are maintained at a potential which is positive to the cathode of the electron gun, while the film 35 is positive to the electrodes of the grid. Superimposed upon these potentials are the micro-deflecting potentials between the sets of grid wires 23 and 25, a "grid potential," when referred to hereinafter, signifying the mean potential of these grid wires.

The design of a tube of this character is predicated upon specific ratios between the various potentials involved, the ratio of the grid-to-screen potential to the cathode-to-grid potential determining the focussing of the beam. The ratio of the deflecting potential to the others mentioned determines the direction and magnitude of the micro-deflection of the beam and whether it falls upon a red, green, or blue phosphor when it enters the aperture between any pair of grid wires. The amount that the beam is deflected from its straight-line course by its focussing action depends both upon the relative potentials of the cathode, grid, and screen, and its angle and direction of deflection about the center of deflection indicated by the point 7 in Fig. 1.

It has previously been shown that the three fundamental qualities which affect the operation of the tube, i. e., refraction, deflection sensitivity, and width of focus, may be defined by the following equations:

Refraction: In terms of displacement from perpendicular from center of aperture:

$$y = \frac{2D \tan \beta}{1 + \sqrt{1 + V_2/(V_1 \cos^2 \psi)}} \quad \text{Eq. (1)}$$

In terms of difference of displacement from straight line path of the rays between grid and screen:

$$t = D \tan \beta \left(\frac{2}{1 + \sqrt{1 + V_2/(V_1 \cos^2 \psi)}} - 1 \right) \quad \text{Eq. (1a)}$$

Deflection sensitivity:

$$\Delta y_d = \frac{\pi D V_d}{2 V_1 \ln \frac{4s}{\pi w}} \left[\frac{\cos^2 \beta / \cos^2 \psi}{1 + \sqrt{1 + V_2/(V_1 \cos^2 \psi)}} \right] \left[1 + \frac{\tan^2 \beta}{\sqrt{1 + V_2/(V_1 \cos^2 \psi)}} \right] \quad \text{Eq. (2)}$$

Focal width:

$$y_f = (s-w) \left\{ 1 - \frac{V_2}{V_1} \left[\frac{\cos^2 \beta / \cos^2 \psi}{1 + \sqrt{1 + V_2/(V_1 \cos^2 \psi)}} \right] \right\} \left[1 + \frac{\tan^2 \beta}{\sqrt{1 + V_2/(V_1 \cos^2 \psi)}} \right] \quad \text{Eq. (3)}$$

The notation used in these equations, and those which will follow, is as follows:

D =length of normal dropped from grid aperture pierced by beam to screen

s =grid wire pitch

w =grid wire diameter

V_1 =voltage between cathode and grid

V_2 =voltage between grid and screen

ψ =total angle between beam arriving at grid plane and normal dropped from grid aperture pierced by beam

β =projection of ψ on plane normal to grid wires

5 α =projection of ψ on plane parallel to grid wires which contains the normal to the grid aperture pierced by the beam

r =distance from beam impact position at screen to normal dropped from grid aperture pierced by beam

10 y =projection of r on plane normal to grid wires

t =refraction=deflection of beam from rectilinear paths between grid and screen

These equations hold where the grid and screen are in parallel planes, and they are sufficiently accurate for practical purposes with screen and grid curvatures such as are met with in tubes such as are considered here if it be assumed that for any small area impacted by the beam the grid is a plane tangent to its actual surface and the screen lies in a parallel plane at a distance D equal to the actual distance between the structures measured along a perpendicular dropped from the grid. For planar grids and screens the quantity D is a constant throughout the target area and the angle of incidence ψ is substantially the angle of scanning deflection. With curved grids and screens the quantity D may become a variable, and the angle ψ is in general less than the angle of deflection.

15 The problems in tube construction arise from the fact that all three of the important quantities vary continuously, and nonlinearly with both the angle of incidence ψ and its tangent, and that they do not vary in exactly the same manner.

20 Each of the above equations shows that the quantity involved varies at an increasing rate with increasing angle of incidence at the grid. Equations 2 and 3 also show that the variation in size of the focal spot and the sensitivity to deflection both vary most rapidly for deflections parallel to the direction of the grid conductors; so much so, in fact, that in the case of the planar grid and screen the amount

25 of variation in these quantities is nearly twice as great if the grid conductors run parallel to the longer dimension of the screen as is the case if they run parallel to the shorter dimension.

30 The problems in tube construction arise from the fact that all three of the important quantities vary continuously, and nonlinearly with both the angle of incidence ψ and its tangent, and that they do not vary in exactly the same manner.

35 Each of the above equations shows that the quantity involved varies at an increasing rate with increasing angle of incidence at the grid. Equations 2 and 3 also show that the variation in size of the focal spot and the sensitivity to deflection both vary most rapidly for deflections parallel to the direction of the grid conductors; so much so, in fact, that in the case of the planar grid and screen the amount

40 of variation in these quantities is nearly twice as great if the grid conductors run parallel to the longer dimension of the screen as is the case if they run parallel to the shorter dimension.

45 According to the preferred form of the present invention, therefore, the axis of the cylindrical grid is in a plane parallel to the shorter dimension of the screen. The radius of curvature of the grid is greater than the distance from the center of deflection of the cathode-ray beam to the grid, in order to avoid excessive curvature of the viewing surface, but even so, the angle of incidence ψ is greatly decreased, so that the variation in the three important parameters is not only reduced but becomes much more nearly linear. Finally, in order to compensate for the angular variation in sensitivity to deflection,

50 the screen, too, is preferably made concave as viewed from the source of the electron beam, preferably with a different degree of curvature from that applied to the grid, so that the grid-screen distance becomes less as the sensitivity to deflection increases, and the displacement of the focal spot thus may be held nearly constant. Best compensation is obtained when the radii of curvature differ in the two dimensions, being longer in the plane parallel to the axis of the grid. A very considerable degree of compensation can be obtained, however, by making the screen with an infinite radius of curvature in the direction of the grid axis (i. e., a cylindrical screen) or with a spherically curved screen, which it may be advisable to use for reasons of screen manufacture.

55 In order to design target structures in accordance with these principles it is necessary to express the quantities D , ψ and β in terms of the cylindrical coordinates of the grid, i. e., the angle δ , between the plane including the axis of the grid and the undeflected beam and the plane including the grid axis and the point of penetration of

60 the beam at the grid, and h , the distance of the point of

65 the beam at the grid, and h , the distance of the point of

70 the beam at the grid, and h , the distance of the point of

75 the beam at the grid, and h , the distance of the point of

impact from the plane normal to the grid axis which includes the path of the undeflected beam.

The equations involved are as follows:

$$\tan \alpha = \frac{h}{(R_s - J \cos \delta)} \quad (4)$$

$$\tan \beta = \frac{(J \sin \delta)}{(R_s - J \cos \delta)} \quad (5)$$

$$\frac{1}{\cos^2 \psi} = 1 + \frac{h^2 + J^2 \sin^2 \delta}{(R_s - J \cos \delta)^2} \quad (6)$$

In the above equations J = the distance between the center of deflection of the cathode-ray beam and the axis of the cylindrical grid and R_s = the radius of the grid.

The expression for the quantity D differs in form slightly as between cylindrical, spherical, and compound-curved screens. For a cylindrical screen:

$$D = \sqrt{R_s - (K \sin \delta)^2 + K \cos \delta - R_s} \quad (7)$$

For a spherical screen:

$$D = \sqrt{(R_s - h^2) - K^2 \sin^2 \delta + K \cos \delta - R_s} \quad (8)$$

In both of these equations K = the distance the center of curvature of the screen is displaced toward the grid from the grid axis, and R_s is the radius of curvature of the screen at the point of impact, in the plane of deflection of the beam.

With a tube of given external dimensions one method of design, by the use of the above equations, is to determine first the parameters of the grid which is to be used, solve the equations for variation in focus and sensitivity, giving the latter in terms of the screen distance D , and finally, through the use of the equations, choose radii of curvature for the screen so that D will vary inversely as its coefficient in the solutions.

The closest approximation to uniformity of deflection sensitivity can be achieved with a screen having a "barrel-shaped" surface; i. e., a surface which is generated by rotating an arc of long radius around the axis on a shorter radius. In this case the equations for a cylindrical screen may be applied to obtain the values of the shorter radii in the planes passing through center and the edges of the screen. The longer radius of the screen is that of a circle passing through the ends of these radii.

This construction leads to screens which are very nearly cylindrical; in a tube having a maximum angle of deflection θ of 35° , with a projected screen area of $10\frac{1}{2} \times 14$ inches and a distance from the center of deflection to the screen of $13\frac{1}{2}$ inches, it leads to minor radii of approximately 27 inches and major radii in the neighborhood of 150 inches, with a difference between the lengths of the minor radii at the center and ends of the screen of somewhere in the neighborhood of $\frac{1}{10}$ inch. Using a grid wire spacing of 30 mils and a ratio V_2/V_1 of 2.76, the variation in spot size at the extremes of the X and Y axes is only about 1.8 mils. This is less than one-half of the minimum variation obtainable with a flat grid and the same angles of deflection. The variation in effective sensitivity to deflection, over the screen surface, is reduced to one or two percent.

Using a cylindrical screen with the same type of grid, the variation in sensitivity to deflection becomes somewhat greater, but is still only about one-half of that obtained with planar grids and screens.

Where the screen is formed directly on the window at the end of the tube, a screen cylindrical or nearly cylindrical in form is more difficult to manufacture than that employing a spherical surface. For the purpose of economy of manufacture, it may therefore be desirable to use a compromise design wherein the sensitivity to deflection is permitted to vary but the variation in focus is held to a minimum. A tube having a spherical-surface screen, with a 40 inch radius and with a center of curvature of the screen on the axis on the cylindrical grid and with one

inch maximum separation between grid and screen will have the following characteristics:

Point	Refraction Correction	Deflection	Focusing
Center of Screen	0	1	+.06
Center of Vertical Edge	.10	1.025	.04
Center of Horizontal Edge	0	.71	.06
Corner of Screen	.076	.71	-.06

10

This is assuming a voltage ratio $\frac{V_2}{V_1} = 2.75$.

Such a construction leads to a large improvement in variation in focal-spot size as compared to a flat grid and screen. The variation in deflection sensitivity is substantially the same as in the case of the planar grid and screen.

It should be evident that an infinite number of variations is possible between a cylindrical or nearly cylindrical screen surface and a spherical surface, thus offering a compromise between ease of manufacturing construction and uniform sensitivity to deflection. The use of the curved grid, however, always reduces the variation in spot size. This, of itself, leads to improved performance, since in order to prevent color contamination in the picture displayed it is desirable to blank the spot during the intervals when it is passing over the junction between two adjacent strips of phosphor. The faster the spot is traveling when it crosses the junction between two phosphors the larger it may be for a given blanking interval.

With such a cylindrical grid and spherical screen the maximum sensitivity to deflection occurs at the center of the screen, instead at the ends of the strips as is the case with planar structures. For this reason it may be desirable to choose the value of V_2/V_1 so that minimum spot size is obtained nearer to the edges of the screen instead of equalizing the increase in size due to over-focusing at the edges and under-focusing at the center. By making the phosphor strip which is electro-optically centered with the centers of the corresponding apertures wider than the two adjacent strips, electro-optically centered under the electrodes, minimum blanking time may thus be obtained.

Experience has indicated that owing to the scattering of both electrons and light in the phosphor, and of aberrations of the electron-optical lenses, the minimum size of spot which can be obtained is approximately 3 mils in width. By adjusting the value of V_2/V_1 so that the degree of over-focus at the edges is about one-third of the degree of under-focus at the center of the screen the transition time can be equalized and optimum performance obtained.

The advantages in regard to its variation in size in focal spot and variation in deflection sensitivity have been emphasized throughout this specification because it is always possible to devise a screen which will properly take account of refraction. Methods of closely approximating the exact corrections by dividing the target area into zones are described in the prior art. Nevertheless there is a definite advantage in the use of the cylindrical grid even so far as refraction is concerned, since, with the smaller effective angles of incidence resulting from its use, the variation in refraction becomes much more nearly linear and if refraction is to be compensated for by any of the approximate methods, which divide the screen area into zones, the number of zones used can be reduced or, alternatively, the residual errors between zones may be minimized if the same number of zones are employed as for a flat grid.

It may be of interest to note the effect of other grid and screen conformations. By increasing the radii of curvature of either a cylinder or a sphere the result, in the limit, is a flat screen. As has been pointed out, the use of a concavely cylindrical grid improves the overall focusing to the same degree, irrespective of the curva-

ture of the screen, since electron lenses of the type here described result in the same variation in size of focal spot with variation in the angle of incidence of the beam irrespective of the separation D between screen and grid. If, in the limiting case, the concavely cylindrical grid is used with a flat screen, the improvement in focus will be the same as with a concave screen. The variation in sensitivity of deflection may be either greater or less than with a flat grid, depending upon whether the percentage variation in D resulting from the greater distance between grid and screen at the edges of the structure is greater or less, proportionally, than the variation in angular sensitivity; with relatively large minimum values of D there may, therefore, be improvement in performance even in the case of a flat screen with the concave grid.

If a convex grid were used, the variation in effective angle of incidence would be greatly increased, the variation in focus would be increased, and although the variation in sensitivity might possibly be decreased at some particular value, in general the whole performance of the tube would be deteriorated.

In the case of tubes wherein the color displayed depends upon the angle of incidence of the beam at the grid and not upon micro-deflection, the problem of deflection sensitivity no longer appears as such but since the variation in angle of incidence has an effect generally similar to micro-deflection with respect to the points of beam impact on various portions of the screen the concave grid can still give improved results with proper screen configuration.

So many different parameters and manufacturing considerations are involved in the structure of a color tube that it is not practical or even possible to define a "best" combinations of parameters. Different engineers will choose different combinations to meet specific conditions of manufacturing simplicity, ruggedness of structure, and uniformity of operation throughout the screen area. The various examples given herein are illustrative, therefore, rather than limiting conditions. These examples are therefore not intended to be considered as limiting the scope of the invention, the intended limitations being set forth specifically in the following claims.

What is claimed is as follows:

1. In a cathode-ray tube for the display of television images in color, comprising an evacuated envelope and an electron gun therein adapted to direct an electron beam against a viewing area at one end thereof over which the beam is adapted to be deflected about a center of deflection to scan said viewing area, a target structure within said viewing area comprising a transparent base having a substantially uniformly curved concave surface facing said electron gun, a grid of tightly stretched linear conductors mounted adjacent to said base, said conductors being disposed along elements of a cylindrical surface having its axis substantially parallel to an axis of symmetry of said concave surface and being mutually spaced by distances of the order of magnitude of one elemental area of the television image to be reproduced, and a display screen deposited on the concave surface of said base and comprising strips of different phosphors respectively emissive on electron impact of light of the component colors of an additive color system and disposed in a repeating pattern of groups, each of which includes at least one strip of each of said phosphors, the center of each group being electro-optically aligned with the center of the interspace between an adjacent pair of electrodes of said grid.

2. In a cathode-ray tube for the display of television images in color, comprising an evacuated envelope and an electron gun therein adapted to direct an electron beam against a viewing area at one end thereof over which the beam is adapted to be deflected about a center of deflection to scan said viewing area, a target structure within said viewing area comprising a transparent base having a substantially spherically curved concave surface facing

- 5 said electron gun, a grid of tightly stretched linear conductors mounted adjacent to said base, said conductors being disposed along elements of a cylindrical surface having its axis substantially parallel to the chord of said spherical surface and being mutually spaced by distances of the order of magnitude of one elemental area of the television image to be reproduced, and a display screen deposited on the concave surface of said base and comprising strips of different phosphors respectively emissive on electron impact of light of the component colors of an additive color system and disposed in a repeating pattern of groups, each of which includes at least one strip of each of said phosphors, the center of each group being electro-optically aligned with the center of the interspace between an adjacent pair of electrodes of said grid.
- 10 3. The combination as defined in claim 2 wherein the center of said spherical surface and the axis of the cylinder defined by said grid are each more distant from said target structure than the center of deflection of said beam.
- 15 4. In a display tube for television signals including means for directing a beam of electrons in a direction substantially normal to a target area over which it is adapted to be deflected bidirectionally to scan a raster, 20 target structure within said area comprising a grid of parallel linear conductors disposed in two mutually insulated, interleaved sets and defining a cylindrical surface, connections for applying potential differences between said sets to produce a micro-deflection of electrons passing therebetween, and a display screen mounted adjacent to said grid and comprising a transparent base, strips of phosphors emissive on electron impact of light of different colors additively producing white disposed on said base in a repeating pattern of groups including all of said phosphors, the center of each group being electro-optically aligned with the center of an interspace between adjacent conductors of said grid, and a conductive coating on said phosphors adapted to form with said grid elements of a multiplicity of electron lenses, the phosphor-coated surface of said base being concavely curved with respect to said grid in at least one dimension so that the separation between said grid and screen varies from point-to-point over the surface thereof as an inverse function of the angle of incidence of said beam at said grid when deflected thereto.
- 25 5. In a display tube for television signals including means for directing a beam of electrons in a direction substantially normal to a target area over which it is adapted to be deflected bidirectionally to scan a raster, 30 target structure within said area comprising a grid of parallel linear conductors disposed in two mutually insulated, interleaved sets and defining a cylindrical surface, connections for applying potential differences between said sets to produce a micro-deflection of electrons passing therebetween, and a display screen mounted adjacent to said grid and comprising a transparent base, strips of phosphors emissive on electron impact of light of different colors additively producing white disposed on said base in a repeating pattern of groups including all of said phosphors, the center of each group being electro-optically aligned with the center of an interspace between adjacent conductors of said grid, and a conductive coating on said phosphors adapted to form with said grid elements of a multiplicity of electron lenses, the phosphor-coated surface of said base being concavely curved with respect to said grid in at least one dimension so that the separation between said grid and screen varies from point-to-point over the surface thereof as an inverse function of the angle of incidence of said beam at said grid when deflected thereto.
- 35 6. In a display tube for television signals including means for directing a beam of electrons in a direction substantially normal to a target area over which it is adapted to be deflected bidirectionally to scan a raster, 40 target structure within said area comprising a grid of parallel linear conductors disposed in two mutually insulated, interleaved sets and defining a cylindrical surface, connections for applying potential differences between said sets to produce a micro-deflection of electrons passing therebetween, and a display screen mounted adjacent to said grid and comprising a transparent base, strips of phosphors emissive on electron impact of light of different colors additively producing white disposed on said base in a repeating pattern of groups including all of said phosphors, the center of each group being electro-optically aligned with the center of an interspace between adjacent conductors of said grid, and a conductive coating on said phosphors adapted to form with said grid elements of a multiplicity of electron lenses, the phosphor-coated surface of said base being concavely curved with respect to said grid in at least one dimension so that the separation between said grid and screen varies from point-to-point over the surface thereof as an inverse function of the angle of incidence of said beam at said grid when deflected thereto.
- 45 7. In a display tube for television signals including means for directing a beam of electrons in a direction substantially normal to a target area over which it is adapted to be deflected bidirectionally to scan a raster, 50 target structure within said area comprising a grid of parallel linear conductors disposed in two mutually insulated, interleaved sets and defining a cylindrical surface, connections for applying potential differences between said sets to produce a micro-deflection of electrons passing therebetween, and a display screen mounted adjacent to said grid and comprising a transparent base, strips of phosphors emissive on electron impact of light of different colors additively producing white disposed on said base in a repeating pattern of groups including all of said phosphors, the center of each group being electro-optically aligned with the center of an interspace between adjacent conductors of said grid, and a conductive coating on said phosphors adapted to form with said grid elements of a multiplicity of electron lenses, the phosphor-coated surface of said base being concavely curved with respect to said grid in at least one dimension so that the separation between said grid and screen varies from point-to-point over the surface thereof as an inverse function of the angle of incidence of said beam at said grid when deflected thereto.
- 55 8. In a display tube for television signals including means for directing a beam of electrons in a direction substantially normal to a target area over which it is adapted to be deflected bidirectionally to scan a raster, 60 target structure within said area comprising a grid of parallel linear conductors disposed in two mutually insulated, interleaved sets and defining a cylindrical surface, connections for applying potential differences between said sets to produce a micro-deflection of electrons passing therebetween, and a display screen mounted adjacent to said grid and comprising a transparent base, strips of phosphors emissive on electron impact of light of different colors additively producing white disposed on said base in a repeating pattern of groups including all of said phosphors, the center of each group being electro-optically aligned with the center of an interspace between adjacent conductors of said grid, and a conductive coating on said phosphors adapted to form with said grid elements of a multiplicity of electron lenses, the phosphor-coated surface of said base being concavely curved with respect to said grid in at least one dimension so that the separation between said grid and screen varies from point-to-point over the surface thereof as an inverse function of the angle of incidence of said beam at said grid when deflected thereto.
- 65 9. In a display tube for television signals including means for directing a beam of electrons in a direction substantially normal to a target area over which it is adapted to be deflected bidirectionally to scan a raster, 70 target structure within said area comprising a grid of parallel linear conductors disposed in two mutually insulated, interleaved sets and defining a cylindrical surface, connections for applying potential differences between said sets to produce a micro-deflection of electrons passing therebetween, and a display screen mounted adjacent to said grid and comprising a transparent base, strips of phosphors emissive on electron impact of light of different colors additively producing white disposed on said base in a repeating pattern of groups including all of said phosphors, the center of each group being electro-optically aligned with the center of an interspace between adjacent conductors of said grid, and a conductive coating on said phosphors adapted to form with said grid elements of a multiplicity of electron lenses, the phosphor-coated surface of said base being concavely curved with respect to said grid in at least one dimension so that the separation between said grid and screen varies from point-to-point over the surface thereof as an inverse function of the angle of incidence of said beam at said grid when deflected thereto.
- 75 10. In a display tube for television signals including means for directing a beam of electrons in a direction substantially normal to a target area over which it is adapted to be deflected bidirectionally to scan a raster, target structure within said area comprising a grid of parallel linear conductors disposed in two mutually insulated, interleaved sets and defining a cylindrical surface, connections for applying potential differences between said sets to produce a micro-deflection of electrons passing therebetween, and a display screen mounted adjacent to said grid and comprising a transparent base, strips of phosphors emissive on electron impact of light of different colors additively producing white disposed on said base in a repeating pattern of groups including all of said phosphors, the center of each group being electro-optically aligned with the center of an interspace between adjacent conductors of said grid, and a conductive coating on said phosphors adapted to form with said grid elements of a multiplicity of electron lenses, the phosphor-coated surface of said base being concavely curved with respect to said grid in at least one dimension so that the separation between said grid and screen varies from point-to-point over the surface thereof as an inverse function of the angle of incidence of said beam at said grid when deflected thereto.

to be deflected bidirectionally to scan a raster, target structure within said area comprising a grid of parallel linear conductors disposed in two mutually insulated, interleaved sets and defining a cylindrical surface, connections for applying potential differences between said sets to produce a micro-deflection of electrons passing therebetween, and a display screen mounted adjacent to said grid and comprising a transparent base, strips of phosphors emissive on electron impact of light of different colors additively producing white disposed on said base in a repeating pattern of groups including all of said phosphors, the center of each group being electro-optically aligned with the center of an interspace between adjacent conductors of said grid, and a conductive coating on said phosphors adapted to form with said grid elements of a multiplicity of electron lenses, the phosphor-coated surface of said base being concavely curved with respect to said grid with different degrees of curvature in the two dimensions, so that the separation between grid and screen varies from point-to-point with the variation in angle of incidence of said beam at said grid and varies more rapidly with angles of incidence parallel to the direction of the electrodes of said grid than with angles of incidence normal thereto.

7. In a cathode-ray tube for displaying television images in color which includes a screen having a repeating pattern of strips of phosphors emissive of different colored light deposited thereon and an electron gun for directing against said screen a beam of electrons adapted to be bidirectionally deflected thereacross about a center of deflection screen, a grid of tightly stretched linear conductors mounted adjacent to said screen, the conductors of said grid being disposed generally parallel to the phosphor strips comprising said pattern and defining a cylindrical surface having an axis more distant from said screen than said center of deflection, said surface being concave as viewed from said electron gun.

35

8. A grid as defined in claim 7 wherein the conductors of said grid comprise two mutually insulated interleaved sets.

9. In a cathode-ray tube for displaying television images in color, including an electron gun for directing a beam of cathode rays against a target area over which said beam is adapted to be bidirectionally deflected about a center of deflection to trace a raster, a grid of tightly stretched substantially parallel linear conductors disposed in a cylindrical surface mounted in said target area, said surface being concave toward said electron gun and having a radius of curvature greater than the distance of said center of deflection to said grid, and a screen mounted behind said grid in said target area and concave as viewed from said electron gun and comprising a transparent base plate and a repeating pattern of strips of different phosphors deposited thereon, said strips being generally parallel to said linear conductors, said screen being so curved as to be nearer to said grid at the ends of said linear conductors than at the centers thereof.

10. The combination as defined in claim 9 wherein the dimensions of said grid and screen are less in the direction of the axis of said grid than in the direction normal to said axis.
